HAND BRUSH

Wong Bing Goon, 645 First St., San Diego, Calif.

Filed Apr. 27, 1959, Ser. No. 55,664

Term of patent 3½ years

(Cl. D9—2)

Fig. 1

Fig. 2

Fig. 3

Fig. 4

Fig. 5

I claim:

The ornamental design for a hand brush, as shown.
